UNITED STATES PATENT OFFICE.

WILLIAM W. COLEMAN, OF NEW YORK, N. Y.

RAIL-BRACE.

1,355,814.

Specification of Letters Patent. Patented Oct. 19, 1920.

Application filed March 26, 1920. Serial No. 369,037.

To all whom it may concern:

Be it known that I, WILLIAM W. COLEMAN, a citizen of the United States and a resident of the city of New York, county of 5 New York, and State of New York, have invented a new and useful Improved Rail-Brace, of which the following is a specification.

This invention relates to railway tracks 10 and more particularly to means for bracing the rails thereof.

An important object of the invention is to provide an adjustable brace or rail support of novel construction for use more 15 especially at the junction of switch points with the main rail and upon curves to prevent spreading of the rails, and also for readily compensating for wear upon the inner side of rail heads, and for any variations 20 in gage which may result from climate changes or other conditions.

Other objects and advantages will appear as the description of the invention progresses, and the novel features of the invention will 25 be particularly pointed out in the appended claims.

The invention consists in the combinations, constructions and arrangements herein described and claimed.

30 In describing the invention in detail, reference is had to the accompanying drawing, wherein a preferred physical embodiment of the invention has been illustrated, and wherein like characters of reference designate 35 corresponding parts throughout the several views, and in which:

Figure 1 is a perspective view of the improved rail brace as applied to a rail; Fig. 2 is a cross sectional elevation of the improved 40 rail brace as applied to a rail; Fig. 3 is a top plan view of the improved rail brace as applied to a rail; Fig. 4 is a front elevational view of a bracket forming part of the improved rail brace; and Fig. 5 is a perspective 45 view of a modified improved rail brace.

The specific embodiment of the invention which has been selected for illustration by a drawing in order to impart a better understanding of the invention is shown in Fig. 50 1 as applied to a rail 1. The rail 1 rests upon the usual iron tie plate 2, which in turn rests upon the tie 3, buried in the ballast 4.

55 A circular cavity 5, best shown in Fig. 2, is formed in the tie plate 2. Within this

cavity and completely filling the same is a circular depending integral boss 6 of a bracket 7. This construction allows bracket 7 to swivel on the tie plate. 60

The bracket 7 has a projecting wedge shaped face 8 which fits into and contacts a similarly but reversely formed face 9 of a block 10.

The block 10, as best shown by Fig. 3, is 65 tapered or wedge shaped longitudinally and as best shown by Fig. 2 fits snugly against the under side of the ball of the rail and against the top of the rail flange. Also, as best shown by Fig. 3, this close contact is 70 maintained throughout the length of the block 10.

By reference to Fig. 3 and particularly the dotted line 11 thereof it will be understood that the bracket 7 is formed with the 75 face 8 tapering longitudinally.

The operation of the construction so far as it has been described will be readily seen to provide a convenient and readily operated means for holding rail 1 to gage or returning it to gage if it has been displaced. The tie-plate 1 as is usual and as is understood, is in practice suitably secured to tie 3. If then the boss 6 of bracket 7 is placed in cavity 5, the bracket forms an immovable 80 member against which block 10 may bear, so that all that is needed to properly position the rail is to move block 10 longitudinally one way or the other until rail 1 is properly positioned, because if the block is struck on the small end the rail may approach bracket 7, but if it is struck on the large end then rail 1 is moved away from bracket 7. 85 90

It will further be evident that as bracket 7 can swivel on boss 6, that contact between block 10 and the rail 1 and between block 10 and bracket 7 is always maintained along the full length of bracket 7 and block 10, because although rail 1 may not be just at a right angle to tie 3, due to the fact that bracket 7 may swivel, the bracket and block 10 will turn so that block 10 rests against the rail along its entire length and the line of pressure from the rail will pass through the center of boss 6. 95 100 105

It will be further evident that the side pressure of rail 1 is transmitted to the tie plate 2 by means of the boss 6.

Although it may not be absolutely necessary in all cases it has been considered best 110 to hold bracket 7 so that boss 6 cannot jump out of cavity 5. This is done by means of

bolt 12, which passes through the bracket and through a washer 13 bearing against the underside of the tie plate. The bolt 12 is formed with a head 14 so that it will not 5 pass through the washer and the head has at least one flat face 15 bearing against a flat face 16 of the washer so that it will not turn when the nut 17 is applied. The washer is prevented from turning by the 10 pressure between tie plate 1 and tie 3 and is aided in not turning by the sharp points 18 sinking into the tie plate.

After block 10 is suitably positioned it is necessary to hold it in such position. This 15 is accomplished by the use of retaining pin 19 positioned in some one of various cut away portions of bracket 7 and of block 10. Bracket 7 has the two semicircular cutaway portions or locking pin recesses, 20 and 21, 20 best seen in Fig. 3, and block 10 has a plurality of semicircular cut away portions or locking pin recesses, 22, also best shown in Fig. 3.

When block 10 has been adjusted so that 25 a locking pin recess of block 10 coincides with a locking pin recess of bracket 7, then locking pin 19 is placed in the registering semi-circular locking pin recesses thus preventing relative movement of bracket 7 and 30 block 10.

In order to provide for fairly minute adjustment and locking, the distance between recesses 20 and 21 is made such that it is not a multiple of the distance between recesses 22, so that by placing pin 19 in either 35 20 or 21, a fairly close adjustment of block 10 is obtained.

As pin 19 may be readily lifted from the locking recesses by unauthorized persons if 40 not secured, means have been provided for preventing such unauthorized removal. Beneath each of recesses 20 and 21 fins 23 and 24 are placed, preferably integral with the bracket, and pin 19 has been formed with a 45 recess 25, into which a fin enters when the locking pin is pushed downwardly and if then the pin is given a blow on its head the ends of the pin will be spread by the fin and so prevent its removal except by one having 50 a claw bar or like instrument.

In Fig. 5 a modified form of locking means are shown which although basically the same as that shown in Figs. 1 to 4 inclusive, yet is somewhat differently constructed. It 55 in a sense is the reverse of the construction shown in Figs. 1 to 4, inclusive, because the two locking pin recesses 26 and 27 are formed in block 10, whereas the plurality of locking pin recesses are formed in bracket 7, 60 otherwise it is like the one shown in Figs. 1 to 4 inclusive.

From the description in connection with the drawing of one physical embodiment of the invention it will readily be seen that a 65 rail brace has been produced which consists

of only a few easily manufactured parts which are strong and rigid and not easily broken and that the brace is readily and easily assembled and is further easily adjusted and readily and securely locked in 70 adjusted position.

Although the construction of one physical embodiment of the invention has been particularly described and the operation and principle thereof explained, nevertheless it 75 is desired to have it understood that the form selected is merely illustrative but does not exhaust the possible physical embodiments of the idea of means underlying the invention. 80

What is claimed as new and is desired to be secured by Letters Patent of the United States is:

1. In an adjustable rail brace, in combination: a tie plate; a bracket pivotally connected to the tie plate; a rail; a block bearing against the rail, said block and said bracket having reversely formed wedge shaped mutually engaging faces and each being formed reversely tapered longitudinally and means for maintaining a fixed relation between the block and the bracket. 85 90

2. In an adjustable rail brace, in combination: a rail; a block bearing against the rail; a bracket bearing against the block, 95 said block and said bracket being reversely tapered longitudinally of the rail, and relatively adjustable; means for holding said block and said bracket in relative adjustment including a plurality of mutually 100 registrable cavities in the block and in the bracket, a pin for insertion in said cavities and means for holding said bracket from movement.

3. In an adjustable rail brace, in combination: a rail; a block bearing against the rail; a bracket bearing against the block, said bracket and said block being reversely tapered longitudinally of the rail; a locking pin; mutually registering cavities in 110 the block and in the bracket for receiving the pin said pin formed with a bifurcated end and said bracket formed with a member for spreading said pin. 105

4. In an adjustable rail brace, in combination: a rail; a block bearing against the rail; a bracket bearing against the block, said bracket and said block being reversely tapered longitudinally of the rail; a locking pin; mutually registering cavities in the block and in the bracket for receiving the pin said pin formed with a bendable end and means for bending said end. 115 120

5. In an adjustable rail brace, in combination: a rail; a block bearing against the rail; a bracket bearing against the block, said bracket and said block being reversely tapered longitudinally of the rail; a locking pin; mutually registering cavities in the block and in the bracket for re- 125 130

ceiving the pin, said pin formed with a bifurcated end and means for spreading each of the parts formed by the bifurcation.

5. 6. In an adjustable rail brace, in combination: a rail; a block bearing against the rail; a bracket bearing against the block, said bracket and said block being reversely tapered longitudinally of the rail and said 10 bracket formed with a circular boss, and a tie plate formed with a cavity into which said boss fits.

7. In an adjustable rail brace, in combination: a rail; a block bearing against the 15 rail; a bracket bearing against the block, said bracket and said block being reversely tapered longitudinally of the rail and said bracket formed with a circular boss, a tie

plate formed with a cavity into which said boss fits and means for holding said bracket 20 and said tie plate in engagement.

8. In an adjustable rail brace, in combination: a rail; a block bearing against the rail; a bracket bearing against the block, said bracket and said block being reversely 25 tapered longitudinally of the rail and having mutually engaging reversely formed wedge shaped faces; a locking pin; said bracket and said block formed with mutually registrable cavities for receiving 30 said pin and said pin being bifurcated on its end; means entering the bifurcation for spreading the end of the pin; a tie plate and means for holding the bracket in engagement with the tie plate.

W. W. COLEMAN.
